GAS RELEASE CONTROL VALVE FOR AN INSECTICIDE BOMB

Stanton H. Petry, Evanston, Ill.

Application January 15, 1948, Serial No. 143,813

Term of patent 3½ years

(Cl. D31—3)

To all whom it may concern:

Be it known that I, Stanton H. Petry, a citizen of the United States, residing at Evanston, in the county of Cook and State of Illinois, have invented a new, original, and ornamental Design for a Gas Release Control Valve for an Insecticide Bomb, of which the following is a specification, reference being had to the accompanying drawing, constituting a part thereof:

Fig. 1 is a side elevational view of a gas release control valve for an insecticide bomb showing my new design;

Fig. 2 is a top plan view;

Fig. 3 is a front elevation view; and

Fig. 4 is a rear elevation view thereof.

I claim:

The ornamental design for a gas release con-

trol valve for an insecticide bomb, substantially as shown.

STANTON H. PETRY.
